UNITED STATES PATENT OFFICE

168,851

FLEXIBLE BOTTLE

Jules Montenier, Chicago, Ill.

Application December 5, 1952, Serial No. 22,567

Term of patent 14 years

(Cl. D58—6)

To all whom it may concern:

Be it known that I, Jules Montenier, a citizen of the United States, residing at Chicago, in the county of Cook and State of Illinois, have invented a new, original, and ornamental Design for Flexible Bottle, of which the following is a specification, reference being had to the accompanying drawing, forming a part thereof.

In the drawing—

Fig. 1 is a front elevational view of a flexible bottle, showing my new design;

Fig. 2 is a side elevational view thereof looking from the left side of Fig. 1;

Fig. 3 is a side elevational view thereof looking from the right side of Fig. 1; and

Fig. 4 is a top plan view thereof.

I claim:

The ornamental design for a flexible bottle, as shown.

JULES MONTENIER.
